UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 13,262, dated August 22, 1882.

Application filed July 21, 1882. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design is composed of the overlapping rectangular figures, the Grecian borders arranged near said figures and at other parts on the ground of the carpet, and the floral and foliage ornamentation, prominent in which are clusters of diverging leaves resembling palm-

trees. The design also includes the L-shaped figures and the adjacent rectangular reticulated figures having two sides parallel with two sides of the L-shaped figures.

I claim—

The design for a carpet, substantially as shown and described.

In testimony whereof I have signed my name to this specification, in the presence of two subscribing witnesses, this 18th day of July, 1882.

THOMAS J. STEARNS.
